UNITED STATES PATENT OFFICE.

JAMES F. HOWIE, OF SEATTLE, WASHINGTON.

CENTRIFUGAL GUN.

1,235,897.

Specification of Letters Patent.

Patented Aug. 7, 1917.

Application filed July 31, 1916. Serial No. 112,202.

To all whom it may concern:

Be it known that I, JAMES F. HOWIE, a citizen of the United States, and resident of Seattle, county of King, State of Washington, have invented certain new and useful Improvements in Centrifugal Guns, of which the following is a specification.

My invention relates to devices designed for the discharge of projectiles, employing as the motive agent centrifugal force. While the device employs no explosive for the discharge of the projectiles, it may presumably be correctly referred to as a centrifugal gun.

The object of my invention is to produce a device which may be employed for the discharge of projectiles at a high rate of speed within moderate distances without the use of explosives and the noise produced by the same.

My invention comprises certain novel features and constructions which are shown in the drawings and which will be described in the specification and then particularly pointed out in the claims.

In the accompanying drawings I have shown the form of construction of my device which is now most preferred by me, although aware that the same features may be employed in constructions differing considerably in appearances from those illustrated and described herein.

Figure 1 is an elevation of the device, the projecting disk and the ring in which it is mounted being shown in section.

Fig. 2 is an elevation of the device taken from a point of view at right angles to that of Fig. 1.

Fig. 3 is a top plan view of the device.

Fig. 4 shows in plan view, partly in section and partly broken away, a portion of the projecting disk and the guiding ring therefor.

My device operates on the principle of giving a projectile a high rotative speed and then discharging it, the direction of the discharge being controlled in such a way as to make it possible to use the device as a means for discharging a projectile at certain objects. It is well known that if a body be released from the periphery of a rapidly rotating disk or wheel it will be discharged some distance.

Distances of this discharge will depend upon the velocity of rotation of the wheel, as well as the direction of the discharge with relation to the horizontal. It is possi-

ble, to mechanically produce, within the limits of the strength of materials available, such velocity of discharge as will secure a range of one to two miles or even 60 very much more. It is not intended that the present invention shall supplant long range guns, but it is contemplated that it shall be used for more moderate ranges in which the rapidity of its discharge and the 65 cheapness of operation will give it material advantages for certain special uses.

I have herein shown my device as mounted upon a base or frame, 1, which has legs 10 extending upward therefrom and carrying, 70 at their upper ends, a ring 12. Upon this base is mounted a yoke frame 2, which also has a ring-like, circular base 24, which preferably fits over the upper ring 12 of the base. These two parts are mounted to turn 75 freely upon each other, as by means of balls 21, which run in grooves in the face of the two members. The yoke frame 2 has two arms 20 extending upward and provided with bearings for the reception of journals 80 41, of a guide ring 4. The guide ring 4 is provided with an inwardly facing groove 40, of semi-circular cross section and is provided with a projectile discharge guide or pipe 42, placed tangential to the ring 4. 85 The guiding groove 40 is intended to closely fit and receive the projectile and the tube 42 serves as the directing tube, corresponding in function with the barrel of a gun. It is preferred that both the walls of the 90 groove 40 and the inner surface of the projectile guiding groove 42 be rifled, as shown by the rifling 44 in Fig. 4.

The ring 4 has a web 45 extending across the same, the central portion thereof being 95 provided with grooves for the reception of balls 43, which balls also fit within a supplemental groove formed in the underside of the under plate of the rotative disk 5, thereby providing a ball bearing upon which 100 the disk may rotate. The projecting disk 5 is composed of two plates having their faces secured together. These disks turn concentrically within the ring 4. They are secured to the stub shaft 80, which shaft is 105 secured by means of a universal coupling 8, with a shaft 3 which is journaled in a bearing 22 of the yoke 2, and any suitable other bearings in the frame 1.

The shaft 3 extends vertically. This shaft 110 is driven in any suitable and convenient manner. The driving means herein shown,

consists of an electric motor 32 having its shaft 31 journaled in bearings 11, carried by the frame or base and having driving connection with the vertical shaft 3 by means 5 of the spiral gears 30 and 33. Any other convenient means for rotating the shaft 3, which is found suitable, may be employed.

The compound disk 5 is provided with one or more projectile feeding channels, 50, 10 extending from a point adjacent its rotating axis, to its outer edge. The bullets which are to be thrown by this machine, are fed into the openings 52 of these channels, which lie adjacent to the rotating axis. These 15 channels extend outwardly, preferably, in a curved shape, as is illustrated in Fig. 3. At their outer ends they open at the periphery of the disk, this being just within and alined with the groove 40 of ring 4. 20 At the outer ends of the supply channel 50, ledges 51 are provided, so placed as to engage the rear end of the projectile 72, when it reaches its outermost position. This ledge provides the means whereby the 25 projectile is made to move at the speed of the periphery of the wheel. When the bullet reaches the beginning of the straight discharge tube 42, it is at this time moving in a tangential direction. It will thus, at this 30 time, escape from the restraint imposed by the guide ring 4 and will thus be discharged from the tube 42.

It is very desirable that any device revolving at the high rate of speed which 35 would be required in order to discharge a projectile to a considerable distance, be maintained in as perfect a balance as possible. To secure this result it is desirable that the projectile feeding or supply channels be provided in pairs, located directly 40 opposite to each other. In the drawings I have shown two such guide channels in the rotative projecting disk.

The ring 4 is provided with a handle 25 45 by which it may be rocked upon its trunnions or pivots 41. This gives the projectiles a greater or less elevation when discharged. One end of the yoke 20 is provided with a handle 23 whereby the yoke, 50 together with the rotative disk carried thereby, may be turned about their vertical axes, thus varying the direction in which the projectiles are being discharged.

Upon the ring 4, in suitable position for 55 the use of the operator, is mounted a bar 6 which extends from the rotative disk, upon which bar is mounted a telescope 60 or any other desired type of aiming apparatus.

60 A truss or arm 7, extends across the machine and is supported from the ring 4. At a point slightly to one side of the center of rotation, a pocket or case 73 is provided for the reception of the projectiles 72. 65 These projectiles may be placed in this re-

ceptacle one at a time, or by the insertion of a clip 71 which contains a number of projectiles properly arranged therein. The lower end of the projectile receiving case 73, extends down fairly close to the upper surface of the rotating projecting disk at its lower end. It is so curved that the projectiles cannot drop out by straight downward movement. One side, however, is open in such a manner that the projectiles may be 75 removed by a movement in the direction of the axis of the projectile.

The rotative disk has a finger 53, preferably projecting laterally just back of each of the openings 52, through which the projectiles are placed in the feed channel 50. A shield 55 is placed just outside the opening 52, to prevent the projectile from being thrown outward before it enters the opening. The relation of these parts is such that as the disk revolves the fingers 53 each time engage the lowermost projectile in the casing and push it out through the opposite edge of the casing where it drops into the hole 52 and is then caused, by the centrifugal effect given thereto, to slide outwardly through the guideway 50. The projectile passes through this guideway, and as it reaches the outer end of the guideway it contacts with the groove 40 of ring 4. To assist in starting the projectile downward into the opening 52, I may provide a fixed deflector plate 74 at the point of delivery, inclined slightly downward. This plate engages the projectile as it leaves the case 73, 100 and starts it downward into the opening 52.

As soon as it reaches this point, the tip or front end of the projectile is freed and is allowed to swing outwardly into a close fit in the groove 40 in said ring. In consequence, the bullet will be carried along until it reaches the inner end of the barrel or tube 42, whereupon the projectile will follow the tangential course which extends through this barrel instead of continuing in 110 the circular direction.

It is contemplated to rotate the projecting disk at as high rate of speed as the strength of material composing the same will permit. It is believed that this will permit a speed of three thousand revolutions per minute. At this rate of speed with a disk of any size, the centrifugal force of a body leaving the periphery of the disk will be sufficient to cause it to travel a great many miles. The discharge of a gun of this kind will produce no explosion and requires no gunpowder. It merely requires a sufficient supply of power to maintain the disk turning at a sufficiently high rate of speed.

What I claim as my invention is:

1. In a centrifugal gun, in combination, a revoluble disk having a projectile supply channel extending from near its center toward its rim, an inclosing rim having a 130

semi-circular projectile fitting groove and a straight discharge tube placed tangential to said groove, the revolving disk having its edge extending well into the said groove 5 and having a shoulder at the outer end of its projectile supply channel to engage the rear end of the bullet, a fixed feed chute over the inner end of the projectile supply channel, and a finger or projection carried 10 by the revolving disk to engage and remove the lowermost projectile from said chute.

2. In a centrifugal gun, in combination, a stand, a yoke having upwardly projecting arms and mounted to turn upon the stand 15 about a vertical axis, a ring having a horizontal axis pivot bearing upon said yoke and having an inwardly facing groove of semi-circular cross section and a discharging tube extending tangentially therefrom, 20 a disk rotatably mounted within said ring and having a projectile feeding channel extending from near its center to its outer edge, the disk having a shoulder at the back side of the outer end of said channel adapted 25 to engage the rear end of the projectile.

3. In a centrifugal gun, in combination, a stand, a yoke having a turntable bearing

upon the stand, a ring pivoted by a horizontal and diametrical axis in the ends of the yoke, and having an inwardly facing, 30 projectile-guiding groove and a tangential discharge channel, a disk mounted to rotate concentrically within the ring and having projectile feeding grooves extending from adjacent its axis to its outer edge, a 35 drive shaft vertically journaled in the yoke concentric with the axis thereof, and a universal coupling connecting said shaft with the projecting disk.

4. In a centrifugal gun, a revoluble projector having a projectile guide extending from near its axis outwardly, a projectile feed having its discharge registering with the receiving end of the guide of the revoluble projector, a projectile feeding finger carried by the revoluble projector and adapted to remove a projectile from the feed device, and a deflector adapted to engage the projectile upon removal from the feed device to deflect it downward into the 50 guide of the projector.

Signed at Seattle, Washington, this 21st day of July, 1916.

JAMES F. HOWIE.
